WICK REMOVER

Walter Nelson, Indianapolis, Ind.

Application December 8, 1934, Serial No. 756,699

4 Claims. (Cl. 67—65)

The present invention has to do in general with the removal of cylindrical wicks, such as are used in the burners of oil stoves of various makes which have become so burned and crusted within

5 the wick holders as to render the operation of removal of the wick an extremely difficult task.

Wicks of the type to which the invention applies are arranged in cylindrical holders forming elements of the burners to permit of the replacement of fresh wicks, when the old ones have burned down to points where their operation is no longer efficient and become so encrusted within the holders it usually involves a difficult, tedious and dirty operation to remove the old wicks 10 and in many instances they must be pried out in sections.

This invention proposes a simple and inexpensive means for removing tightly adherent wicks and one by which the operation may be quickly 20 accomplished and effectively carried out without the usual difficulty and dirt.

In the accompanying drawing, which illustrates the invention and forms a part of this specification:

25 Figure 1 is a central vertical section through a wick holder, wick and wick remover, illustrating the practical application of the invention.

Figure 2 is a perspective view of the improved wick remover, inverted.

30 In Figure 1, there is shown the usual oil stove burner detached from the stove including the cylindrical wick holder 10 having inner and outer walls 11 and 12 in the space between which the cylindrical wick 13 becomes crusted and tightly 35 adherent to the inner and outer walls 11 and 12 of the holder.

The invention proposes a cylindrical remover 15 having spaced inner and outer cylindrical walls or members 16, 17 arranged in concentric 40 spaced relation. The walls 16, 17 correspond in length. The inner wall 16 having a diameter adapting the same to slidably telescope the outer surface of the inner wall 11 of the holder 10, and the diameter of the outer wall 17 of the remover 45 being such that it may slidably telescope the inner surface of the outer wall 12 of the holder. The outer ends of the walls 16, 17 merge into the sides of a flat annulus 17a having a narrow body portion. The annulus 17a in connection with the 50 walls 16, 17 provide an annular wick receiving chamber 17b which is closed at its inner and open at its outer end.

Moreover, the free entering edge of each of the walls 16 and 17 of the remover is serrated 55 throughout to form an annular series of teeth

18 which, when the remover is inserted in the holder constitute a cutting means to cut the encrustation between the inner and outer walls of the holder and the wick 13.

In the use of the improved wick remover 15, 5 it is placed with the free edges of its walls inwardly and outwardly of the wick to be removed, and then with an oscillating movement of the remover it is gradually forced into the wick holder, the teeth 18 effectively cutting the in- 10 crustation between the wick and the holder walls. This operation is continued until the remover is sufficiently deep in the holder to free the wick from the latter, and it then becomes an easy matter to withdraw the wick remover and with it 15 the wick 13 since the latter is frictionally gripped between the walls of the remover as the latter is gradually worked deeper and deeper into the holder. However, since this is a mere friction grip it does not prevent ready disassociation of 20 the wick from the wick remover subsequent to its removal from the holder.

It will be noted that, in the above operation, the dirt and particles of carbon cut from around the wick are held within the wick holder and prevented from flying around and hence the operation, with the present remover, is carried out with a minimum of dirt. Both the holder and the wick 25 remover may be readily cleaned before the insertion of a new wick or subsequent use of the 30 remover for its intended purposes.

What I claim is:

1. A remover for annular wicks comprising a pair of cylindrical members arranged in concentric spaced relation, a flat annulus arranged between and integral with the inner end of said members for connecting them together in spaced relation, said annulus and members coacting to provide an annular wick receiving chamber open at its outer end and closed at its inner end, and 40 each of said members having its outer edge formed with a cutting means.

2. In an implement for removing a wick from a holder having a pair of concentrically arranged spaced walls between which the wick is positioned, 45 a cylindrical inner member of an inner diameter for engaging the inner face of the inner wall of the holder, an outer cylindrical member arranged in concentric spaced relation to the said inner member and of an outer diameter for engaging the 50 inner face of the outer wall of the holder, an annulus having a narrow body, said annulus having its inner and outer edges merging respectively into the inner ends of said inner and outer members, said annulus forming in connection with said 55

members an annular wick receiving chamber closed at its inner end and open at its outer end.

3. In an implement for removing a wick from a holder having a pair of concentrically arranged spaced walls between which the wick is positioned a cylindrical inner member of an inner diameter for engaging the inner face of the inner wall of the holder, an outer cylindrical member arranged in concentric spaced relation to the said inner member and of an outer diameter for engaging the inner face of the outer wall of the holder, an annulus having a narrow body, said annulus having its inner and outer edges merging respectively into the inner ends of said inner and outer members, said annulus forming in connection with said members an annular wick receiving chamber closed at its inner end and open at its outer end, and each of said members having its outer end serrated throughout to provide a cutter.

4. In an implement for removing a wick from a holder having a pair of concentrically arranged spaced walls between which the wick is positioned a cylindrical inner member of an inner diameter for engaging the inner face of the inner wall of the holder, an outer cylindrical member arranged in concentric spaced relation to the said inner member and of an outer diameter for engaging the inner face of the outer wall of the holder, an annulus having a narrow body, said annulus having its inner and outer edges merging respectively into the inner ends of said inner and outer members, said annulus forming in connection with said members an annular wick receiving chamber closed at its inner end and open at its outer end, and each of said members having its outer end serrated throughout to provide a cutter, 5 10 15

WALTER NELSON.
